UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

MEANS OF ATTACHING WORK-SUPPORTS OF SEWING-MACHINES.

1,110,237.

Specification of Letters Patent. Patented Sept. 8, 1914.

Application filed October 16, 1911. Serial No. 654,639.

To all whom it may concern:

Be it known that I, DUDLEY S. SEYMOUR, a citizen of the United States, residing at Oak Park, in the county of Cook, State of Illinois, have invented certain new and useful Improvements in Means of Attaching Work-Supports of Sewing-Machines, of which the following is a description, reference being had to the accompanying drawings and to the letters and figures of reference marked thereon.

My invention relates to an improvement which has been especially devised for use in attaching the work support or cylinder of a sewing machine to the standard thereof. The rear end of this work support on machines of this character, is ordinarily a flat plate having its surface milled and having screw holes for its attachment to the standard. The standard and work support usually contain shafts which for proper working must be in exact alinement, and it is extremely difficult to accomplish such alinement with the two flat engaging surfaces. Furthermore, as the parts within the work support must be kept thoroughly oiled, the oil is likely to leak out between the two contacting faces. I have provided means for preventing such leakage.

A sewing machine of the type to which my invention is applied, is illustrated in Patent No. 583,415, but it will be understood that so far as any broad principle is concerned, I do not wish to be limited to sewing machine construction.

My invention, therefore, consists in the matters hereinafter described and referred to in the appended claims.

The invention is illustrated in the accompanying drawings, in which—

Figure 1 is a side elevation partly in section, of a portion of a sewing machine illustrating an embodiment of my invention; Fig. 2 is an enlarged side section of Fig. 1; Fig. 3 is a perspective view of the end of the work support; and Fig. 4 is a detail view of one of the adjustable bushings.

In these drawings, the standard 1 and the work support or cylindrical casing 2 and the mechanism inclosed within them, are substantially as shown in the patent above referred to. The standard has a flat milled surface with screw holes 3 therein. The casing or work support has a flat rear face 4 with countersunk openings to receive the

heads of the screws 5. It has a journal 3 for the looper shaft 7. Also mounted in the standard is the main cross shaft which operates the feed and vibrates the looper shaft. This main shaft carries the usual eccentric which oscillates the looper shaft 7 about its longitudinal axis. The looper shaft is moved lengthwise in its bearings, through a rock shaft, also mounted in the standard and oscillated from an eccentric connection to the main shaft. This mechanism for oscillating and moving the looper shaft laterally is well known in the art, and further detailed description thereof is not thought necessary.

As heretofore constructed, the casing has been secured to the standard by means of the screws above referred to. By this arrangement of the two flat milled surfaces resting against each other and secured by the four screws, if for any reason it is necessary to disconnect the casing from the standard, it is most difficult to align the shafts in again securing the casing to the standard, as indeed, such is very difficult to do in the manufacture of the machine. By my arrangement, the adjustment of the casing on the standard is rendered more easily accomplished, and accurate shaft alinement secured, and, furthermore, when the adjustment is once effected, the separation of the casing from the standard does not require a new adjustment when the casing is re-attached by the screws, which is the case when screws are both the securing means and the adjusting means.

This improved device invented by me consists in providing adjustable bushings 8, screw-threaded into the casing, bearing at their inner ends on the flat face of the standard and through which the screws 5 pass. These bushings are adjusted by means of a screw driver engaging the nicks 9, and their outer edges are below the countersinks in which the screw heads fit, so that the screw heads do not bear on the bushings but on the casting itself.

It will be seen by this construction that any inequality in the contacting flat faces of the cases and standard, or any other defect, will be compensated for by slight turning of one or another of the bushings.

I do not wish to be limited to this invention as applied merely to the attachment of a sewing machine work support to its stand-

ard, as the same idea may be applied in other constructions.

As a further and special improvement, I have provided means for preventing the leakage of the oil from the casing out through the space between the contacting flat faces. For this purpose, I construct the casing with an apron 10, which passes into the standard and is formed with an under-cut lip 11. By this arrangement, oil runs down the inclined portion 12 of the casing, and is deflected into the standard by the apron, dropping off the same into the standard.

15 Having thus described my invention, what I claim as new and desire to secure by Letters Patent, is:—

1. The combination with a standard, of a frame or casing carried thereby and projecting laterally therefrom, a plurality of devices carried by one of the parts and bearing against the other for adjusting the angular position of the longitudinal axis of the projecting part relative to the stand-

ard, and means for fixedly securing said casing or frame to said standard in its va-

rious adjusted positions.

2. The combination with a standard, of a work support carried thereby and projecting laterally therefrom, both said work support and standard having operating shafts mounted therein, a plurality of devices spaced around said shaft in the work support, and at a distance therefrom, each of said devices being adapted to bear against the standard for adjusting the angular position of the work support with respect to the standard whereby said shafts are placed in proper coöperative relation to each other, and means for fixedly securing the work support to the standard in its various ad-

justed positions.

3. The combination of a standard, a work support carried thereby and projecting laterally therefrom, both said work support and standard having coöperating shafts mounted therein, means for fixedly securing

the work support to said standard, and a plurality of adjustable devices carried by one of said parts and bearing against the other, whereby the angle of the work support relative to the standard may be varied.

4. In combination with a standard and a work support, both containing shafts adapted to coöperate with each other, adjustable bushings carried by one of said parts and bearing against the other to alter the position of said parts, and screws or similar devices passing from the work support into said standard through said bushings, for fixedly holding said work support on the standard.

5. In combination with a standard and work support to be secured together, said work support having internally screw-threaded openings, bushings screwed therein with their outer faces within the plane of the outer end of said openings, screws passing through said bushings into the standard, the heads being out of contact with the bushings.

6. In combination with a standard, a work support secured thereto, said work support opening into the standard, and an apron on said work support projecting into said standard.

7. In a sewing machine, a main frame or standard, a member supported by said main frame, said member having an oil-deflecting portion projecting into the main frame or standard, and means for securing said member to the main frame or standard.

8. In combination with the standard, a work support secured thereto, said work support having an enlarged inner end, the wall of which is inclined downwardly, and an oil-deflecting plate or apron extending from said wall into the standard.

In testimony whereof I affix my signature, in presence of two witnesses.

DUDLEY S. SEYMOUR.
